UNITED STATES PATENT OFFICE

169,726

EAR ORNAMENT OR SIMILAR ARTICLE

Louis Bell, Roxbury, Mass.

Application January 2, 1953, Serial No. 22,991

Term of patent 14 years

(Cl. D45—9)

To all whom it may concern:

Be it known that I, Louis Bell, a citizen of the United States of America, residing in Roxbury, in the county of Suffolk and Commonwealth of Massachusetts, have invented a new, original, and ornamental Design for an Ear Ornament or Similar Article, of which the following is a specification, reference being had to the accompanying drawings forming a part thereof.

Fig. 1 is a front view of an ear ornament embodying my new design; and

Fig. 2 is a side view thereof.

The dominant features of the design reside in the portions shown in full lines.

I claim:

The ornamental design for an ear ornament

or similar article, substantially as shown and described.

LOUIS BELL.
